UNITED STATES PATENT OFFICE.

AMBROSE ALEXANDER, OF MIDDLEVILLE, MICHIGAN.

IMPROVED WASHING-MACHINE.

Specification forming part of Letters Patent No. **56,688**, dated July 31, 1866.

To all whom it may concern:

Be it known that I, AMBROSE ALEXANDER, of Middleville, in the county of Barry and State of Michigan, have invented a new and Improved Mode of Washing Clothes of every description; and I do hereby declare that the following is a full and exact description thereof, reference being had to the accompanying drawing, and to the letters of reference marked thereon, making a part of this specification.

My invention will be fully understood by the drawing, which is a vertical longitudinal central section, in which—

L L represent the frame; M, the washing-box; H, the vertical rubber, supported by the end of the box C; K, the bottom of the washing-box; N, the lid, a partial cover of said box; I, the rubber or wash-board dasher; J, wheels supporting the wash-board dasher, avoiding friction by rolling on the bottom K of the box.

A D E F G is a compound leverage, and is operated in the following way: By pressing the handle A toward the box, D is drawn

forward, which throws F backward, necessarily drawing the dasher G up the inclined plane K of the box. When the dasher or wash-board moves up it leaves the clothes in the machine, so that they turn one-third over at every move of the dasher or wash-board down the inclined plane, not only pressing, but squeezing the clothes between the rubbers at the same time.

Its capacity for washing would be equal in bulk to two double sheets at one washing, thus promoting expedition and economy in washing all kinds of clothing.

What I claim as new, and wish to secure by Letters Patent, is—

The employment of dash-board I with supporting friction-rollers J, in combination with a compound leverage, A, D, E, F, and G, for operating the same, as substantially described.

AMBROSE ALEXANDER.
